UNITED STATES PATENT OFFICE

119,582

DESIGN FOR A SHELVING CABINET

Paul G. Williams and Kenneth C. Welch, Grand Rapids, Mich., assignors to Grand Rapids Store Equipment Company, Grand Rapids, Mich., a corporation of Michigan

Application August 21, 1939, Serial No. 86,814

Term of patent 14 years

To all whom it may concern:

Be it known that we, Paul G. Williams and Kenneth C. Welch, citizens of the United States, residing at the city of Grand Rapids, in the county of Kent and State of Michigan, have invented a new, original, and ornamental Design for a Shelving Cabinet, of which the following is a specification, reference being had to the accompanying drawing, forming a part thereof.

Fig. 1 is a front perspective view of the shelving cabinet showing the new design.

Fig. 2 is a sectional plan view of the same. The ends and the back of the shelving cabinet which are not shown are plain and unornamented.

We claim:

The ornamental design for a shelving cabinet, as shown and described.

PAUL G. WILLIAMS.
KENNETH C. WELCH.
